(57) **CLAIM**

The ornamental design for a flow cell cartridge, as shown and described.

DESCRIPTION

FIG. 1 is a front top right perspective view of a flow cell cartridge showing our new design;

FIG. 2 is a front top left perspective view thereof;

FIG. 3 is rear bottom right perspective view thereof;

FIG. 4 is a front bottom right perspective view thereof;

FIG. 5 is a top view thereof;

FIG. 6 is a bottom view thereof;

FIG. 7 is a left side view thereof;

FIG. 8 is a right side view thereof;

FIG. 9 is a rear view thereof; and,

FIG. 10 is a front view thereof.

The broken lines depict portions of the flow cell cartridge that form no part of the claimed design.
